UNITED STATES PATENT OFFICE

BENGT M. W. HANSON, OF HARTFORD, CONNECTICUT, ASSIGNOR TO PRATT & WHITNEY COMPANY, OF HARTFORD, CONNECTICUT, A CORPORATION OF NEW JERSEY.

METAL-WORKING MACHINE.

971,887.

Specification of Letters Patent.

Patented Oct. 4, 1910.

Application filed February 18, 1909. Serial No. 478,698.

To all whom it may concern:

Be it known that I, BENGT M. W. HANSON, a citizen of the United States, residing at Hartford, in the county of Hartford and 5 State of Connecticut, have invented certain new and useful Improvements in Metal-Working Machines, of which the following is a specification.

This invention relates to metal-working machines one of the primary objects of the invention being to provide effective means for steadyng the work. The machine involves other advantageous points which with the foregoing will be set forth at 10 length in the following description wherein I explain in detail that form of embodiment of the machine which I have selected for illustration in the drawings accompanying and forming part of the present specification, 15 this being to enable those skilled in the art to practice the invention.

My improvements can be incorporated with advantage in many kinds of machines although they are of particular utility when 20 embodied in a metal turning machine whether the work be cylindrical or taper in its nature although the machine will be hereinafter described as organized for securing taper work and in this connection I. 25 might add that the machine which in the present case takes the form of a lathe is peculiarly adapted for turning gun barrels.

Referring to said drawings, Figure 1 is a front elevation of a lathe including my invention. Fig. 2 is a top plan view of said lathe. Fig. 3 is a transverse section of the upper or principal portion of the same, on an enlarged scale. Fig. 4 is a top plan view of a taper bar and certain adjunctive 30 devices. Fig. 5 is a sectional detail of a portion of the cross-slide, operating spring, and certain coöperating parts, and, Fig. 6 is a rear elevation of a supporting bracket and a stringer.

45 Like characters refer to like parts throughout the several figures.

The different parts of the machine may be supported by any suitable framework which is shown as including a bed or base 2 which 50 is of a type familiar in this art or in lathes and which is equipped in practice with the usual legs. As my invention does not concern these features it is needless to go further into detail with respect to the same.

55 While the tool may be supported in any

desirable manner and may be of any suitable nature, it is preferably mounted on a carriage as 4 which is adapted to travel longitudinally of the bed 2 the latter being furnished with ways as 5 and 6 along which 60 said carriage moves. I have shown at 7 the familiar lead screw which serves as a satisfactory medium for reciprocating said carriage and the same may be operated in the usual manner. The carriage 4 presents a 65 main slide and it supports an auxiliary slide as 8 which is the usual cross slide the latter in turn sustaining the tool-slide 9 furnished with the usual appurtenances for holding the tool 10 which is shown as being 70 a turning tool although it is obvious from what I have already stated that the tool might be of some other type while it may be carried in any convenient manner although the means shown and described are quite satisfactory. Between the auxiliary or cross slide 8 and the tool slide 9 I have shown the well known adjustment limiting mechanism which is denoted in a general way by 75 11 and which serves its usual office.

Upon the upper side of the bed 2 are mounted the head stock 12 and the adjustable tail stock 13 between which in the present case the work to be turned or otherwise operated upon is held and said two parts are 80 85 provided with the usual centers 14 and 15 and their well known adjuncts by which the work is supported and rotated.

As I have hereinbefore indicated the machine is adapted to various kinds of work 90 although it is of peculiar utility in turning taper articles of different kinds especially rifle barrels and this class of work can be turned with great precision and exactness on the machine so that in the case of a rifle 95 barrel the latter will not be thinner or thicker cross sectionally at one point than at another.

While the tapering of the work can be secured in different ways I prefer that it be 100 brought about by automatically operating the cross slide 8 transversely to the main slide 4 during the advancing movement of the latter the consequence being that the said cross slide will be caused to follow a 105 path which is at an angle to the axis of motion of the work and which angle corresponds to the taper to be given to said work. A taper bar as 16 serves as a convenient means for causing the cross slide 8 to follow 110

the desired angular path and said bar is shown as having its opposite sides converging toward the tail of the machine and one of these sides is interrupted as will herein-
 5 after appear. In forming a gun barrel while the same is tapered the taper is not straight but is on a curve and for this reason the outer face of the taper bar will be on a similar curve while the inner face thereof
 10 will be straight and in parallelism with the longitudinal axis of said bar 16. Said taper bar or former 16 is shown as removably attached as by screws 17 to the upper side of a plate 18 bolted or otherwise suitably fas-
 15 tened to the bed 2 and located between brackets 19 fastened by screws 20 to the back of the bed 2.

The work is held in a firm and substantial manner by a steady-rest such as that de-
 20 noted in a general way by 21. Not only is the steady rest itself of novel construction but the manner in which the same is sup-
 25 ported is also. Said steady-rest 21 is sus-
 30 tained independently of the tool-carriage or main slide 4, the ways thereof and the usual appurtenances thereon; in other words the said steady-rest does not partake of the motion of the carriage or main-slide. It is normally stationary although I make provi-
 35 sion for adjustment although when said steady-rest is in action it is immovable by reason of which the work can be held in a very rigid manner without in anywise be-
 40 ing marred or similarly affected. A girder or stringer is shown at 22 and it constitutes a suitable device for supporting the body portion 23 of said steady-rest 21. The girder or stringer 22 is illustrated as lo-
 45 cated above the bed 2 and as extending be-
 50 tween and fastened to the upstanding brackets 19, its length being sufficient to ob-
 55 tain the maximum adjustment of the steady-
 rest longitudinally of the bed 2 or in the direction of the axis of motion of the work.

The body portion 23 is shown as consisting of a substantially angular bracket the verti-
 50 cal branch or portion of which fits flatwise against the inner face of the beam or girder 22 the two parts being held together by a
 55 tee bolt 24 the head of which fits a tee groove 25 in the inner face of the said beam or girder. By loosening the nut of said bolt the steady-rest can be adjusted and when the adjustment is obtained it will be main-
 60 tained by setting up said nut which action clamps the body portion 23 tightly against the beam or girder 22.

Preferably the operative portion of the steady-rest engages the work at three cir-
 60 cumferentially separated portions and these are advantageously disposed in triangular order. In this manner I can obtain a suffi-
 65 cient grip upon the work to firmly hold it while the frictional relation between the work and the steady-rest is not excessive

which would be the case were the engage-
 70 ment between the steady-rest and work a continuous or unbroken one. For thus en-
 gaging the work I have represented three anti-friction rollers 26, 27 and 28 the periph-
 75 eries of which are preferably convex to fit an annular groove 29 external of the gun-
 barrel blank 30 and located between the ends of the latter. The gun-barrel blank prior to its being mounted in the lathe has plugs as 31 driven into its opposite open ends and into these plugs the pointed tips of the spin-
 80 dles 14 and 15 are introduced. When the live spindle 14 is turned it will through the usual dog rotate the work. Said dog is not shown in any of the views it being omitted for sake of clearness and for the further fact that it is a very-well known contrivance. The convex portions of these anti-friction rollers by fitting in the annular groove 29 prevent effectually endwise movement of the blank 30. The groove in question may be formed in the blank in any desirable manner. As the tool 10 traverses the work it will pass without touching the circumferential area of the blank in which this groove is formed as will hereinafter appear the consequence being that when the turning operation has been concluded and this occurs when the barrel is nearly to standard size, there will be left on the barrel an integral collar 29' which is dressed off in the finishing or grinding operation.

The anti-friction rollers 26, 27 and 28 are rotatively supported at the inner ends of carriers as 32, 33 and 34 all of which are adjustably mounted so as to adjust their spread or span to adapt them to hold or receive various sizes of work. The several carriers consist of short bars supported by the pendent apron 35 of the body portion or bracket 23. The lowermost carrier 32 is shown as being pivoted at its rear end as at 36 to said apron and as bearing between its ends against the top of an adjusting screw 37 tapped upwardly through a lug 38 on said apron. By operating this screw the raising or lowering of the said carrier 32 can be effected for purposes of adjustment and the adjustment may be maintained by a binding screw as 39 also tapped through said lug 38 and adapted to engage the adjusting screw 37 for such purpose. The carrier 33 is endwise adjustable on said apron 35 it having between its ends a longitudinal slot 40 to receive the shank of the clamping screw 41 tapped into said apron and by loosening which said carrier 33 can be adjusted the same being moved inward by the adjusting screw 42 tapped through a lug 43 on said apron 35 and held against movement when the adjustment is obtained by a binding screw 44 tapped through said lug 43. In this manner the carrier 33 is substantially held against retractive movement or out-

ward thrust when the work is in position. If a given size of work is being operated upon piece after piece it is not my custom to change the position of either of the carriers 32 and 33 the work being removed through the manipulation of the upper carrier 34 which it will be observed is pivoted between its ends as at 45 to said apron 35. The carrier 34 is held to the work by the 10 screw 46 which is shown as tapped through a lug 47 on said apron 35 and the lower end of which engages the forward branch or arm of said carrier or bar 34 to hold said carrier against vibration or chattering and 15 to also maintain an adjustment. The screw 46 can be held against upward displacement by the binding screw 48 also tapped through said lug 47 said binding screw as in the case of the other binding screws being transverse 20 to the holding or adjusting screws. On the body portion or bracket 23 there is a projection 49 which has a screw-threaded opening to receive the plug 50 against the underside of which the coiled push spring 51 is 25 shown as bearing said spring at its lower end bearing against the tail portion of the carrier 34 while its upper portion is received in said screwthreaded opening. The constant or normal tendency of this spring is to 30 elevate or raise the forward portion or branch of the carrier this action when work is in place being effectually resisted by the holding screw 46. When it is necessary to introduce or mount work the screw 46 will 35 be backed out the requisite distance, the action of the screw 48 being first removed if necessary, and as said screw 46 is thus operated the spring 51 will so act against the carrier 34 as to raise the coöperating roller 40 28 so that the desired object can be readily accomplished. When the work is positioned the screw 46 will be operated to move the roller 28 into firm contact with the work after which the binding screw 48 will be 45 set up.

I have described in detail the construction of the steady-rest but I wish it to be distinctly understood that except as required by the scope of the appended claims I do not restrict myself to any of these details nor to the general arrangement disclosed. While a steady rest which engages the work at circumferentially separated points is 50 advantageous for the reasons hereinbefore expressed and while the anti-friction rollers themselves possess advantages it is conceivable that I might otherwise steady the work. As will now appear the work is so engaged that there is no possibility of its moving laterally;—if it did the tool would dig into the work at one point greater than another the result in this event being an inferior output. The product of my machine is absolutely precise and accurate. It will be observed that the two rollers 26 and 28 are

superposed their axes being preferably practically vertically alined and that said rollers are located forward of or on the tool side of a vertical line intersecting the axis of the work while the roller 27 is located approximately opposite the point of the tool 10 and engages the work substantially midway between the points of engagement of the rollers 26 and 28 with said work. By reason of this arrangement any tendency of the tool during the turning operation to draw the work forward or toward the tool is effectually resisted by the two superposed rollers 26 and 28 while backward motion of the work or away from the tool is equally 70 effectually counteracted by the roller 27 which as indicated is practically diametrically opposite the point or tip of the tool. In an ordinary steady rest the usual tendency of the tool in turning work is to draw 75 the work forward and the result is uneven work; this defect I wholly eliminate and can always secure standard work. It will be perceived that there is no direct connection between the three rollers by reason of which 80 they can be independently adjusted and owing to the fact that there is no connection of this kind between the two rollers 26 and 28 the tool can pass the steady-rest without hindrance or without coming in contact 85 with any part thereof although as will hereinafter appear said tool is given an endwise movement by the lateral shifting of the cross slide 8 so that the said tool can clear the groove or channel 29 and therefore leave the 90 latter a relatively permanent part of the blank 30, although as stated the collar 29' left after the turning operation is dressed off by grinding.

Associated with the cross slide 8 which 95 as will be evident constitutes a convenient longitudinally and laterally movable tool-carrying device, is a pair of rollers 52 and 53 which engage the opposite faces of the taper bar 16. The roller 52 is supported by 100 and depends from the block or plate 54 which has a rabbeted connection with the slide 8 and practically forms a rigid part thereof being separably connected therewith by one or more screws as 55. In the rear 105 side of the slide 8 is a horizontal, transverse bore 56 in which is located the endwise movable sleeve 57 and the plate or block 54 to which I have alluded closes the outer end 110 of this bore or passage and prevents the said sleeve from jumping out of the bore under the action of its operating spring 58 which is of push type and the inner end of 115 which bears against the bottom of said bore 57 while the outer end thereof bears against the plug 59 closing the forward end of said sleeve. The spring is inclosed in said sleeve the rear end of the latter being open for the 120 passage of said spring so that the rear end of said spring can act against the bottom of 125 130

said bore. The spring as will be evident normally exerts an advancing thrust to the sleeve through the intervention of the plug. There is shown as formed rigid with said 5 sleeve a stud 60 which depends therefrom and through an elongated slot 61 extending transversely of the slide and in which the stud or pin 60 moves said stud or pin 60 carrying the roller 53 at its lower end. This 10 roller 53 as will be obvious bears against and travels along the inner face of the taper bar which is uninterrupted throughout its length while the complementary roller 52 travels along the outer face of said taper 15 bar which outer face has an inset or jog 16' between its ends. In practice this aperture is located opposite or in transverse line with the steady-rest 21 and it constitutes a suitable let-off or releasing portion of a tem- 20 plet, pattern or taper bar.

In operation the three rollers 26, 27 and 28 will be adjusted to receive the particular size of work to be turned prior to which the bracket or body portion 23 will be moved, 25 if necessary to the desired position. The roller 28 will be then swung up in the manner previously described so that the three rollers can receive the work which is supported between the spindles or centers 14 30 and 15. The carriage or main slide 4 will then be moved to practically the head of the machine, the work in the meantime being held by the conjoint action of the three rollers. The cross slide 8 will then be ad- 35 justed to carry the tool 10 into contact with or substantially into contact with the heel or butt portion of the work, the adjustment limiting means 11 if necessary being utilized. The carriage or main slide 4 is advanced and 40 simultaneously the work is rotated in the manner previously set forth. As the guide rollers 52 and 53 are in contact with the taper bar or templet 16 the cross or auxiliary slide 8 is caused to take an angular 45 path. This slide 8 as will presently appear is diverted out of its normal angular path between the ends thereof so that the tool 10 can clear the annular channel or groove 29 when the roller 52 comes opposite the let 50 off or releasing portion 16'. It will be as- sumed that said roller has reached a place opposite said let off portion. When this occurs the spring 58 thrusts the slide 8 for- 55 ward or toward the front of the machine, which is possible owing to the fact that the roller 53 bears against an uninterrupted face of the taper bar. The slide 8 remains out of its normal path so long as the roller 52 is in the releasing or let off portion 16'. It 60 will be seen that the ends of the relief or let off portion 16' are connected with the outer angular or main face of the taper bar 16 by cam faces 16" and 16'" along the first of which said roller 52 travels in entering 65 the let-off portion 16', the other face 16"

serving to direct said roller 52 onto the outer face of said taper bar at which time the normal path of the cross slide 8 is followed. The let-off portion 16' is made long enough to permit the tool to move away from the 70 work just before the steady-rest 21 is reached and to remain in said condition until said steady rest is safely passed. When the second of the faces 16" acts against the roller 52 to return the cross slide to its nor- 75 mal path the action is in opposition to the spring 58. During the normal travel of the cross slide 8 the spring 58 presses the roller 53 firmly against the inner face of the taper bar 16. 80

I have described fully the machine and its mode of operation so that those conversant with metal working machinery can successfully construct and operate a machine comprising my invention. 85

I do not limit myself to the disclosure made by the present drawings and descriptions for many variations may be adopted within the scope of my claims and I have indicated in a general way some of these 90 variations. It would be quite superfluous to refer to them all. 95

What I claim is:

1. The combination of means for rotatively supporting the work, a tool-supporting carriage mounted for movement in a direction corresponding to the axis of motion of the work, a normally stationary steady-rest supported independently of the carriage, and automatic means for causing the tool to move away from the work when the tool reaches a point in proximity to said steady-rest. 100

2. The combination of a traveling tool-supporting carriage, work-supporting means, a steady-rest supported independently of the carriage, and automatic means for causing the tool to move away from and then approach the work at successive and predetermined points in the travel of the carriage. 105

3. The combination of a bed, a carriage to travel longitudinally of and on said bed, a cross slide supported by the carriage and provided with means for supporting a tool, work supporting means, a steady rest supported independently of the carriage, and automatic mechanism for successively retracting and advancing said cross slide on the carriage during the motion of the latter. 115

4. The combination of a traveling tool supporting device, means for supporting the work, a steady rest supported independently of said tool supporting device, and a forming device and spring means active jointly 120 to move said tool supporting device away from and then toward the work at successive and predetermined points in the travel of said tool supporting device.

5. The combination of work supporting 125

means, a tool carrying device movable in the direction of the axis of the work, a steady rest provided with means for engaging the work at three separated points, two being on the tool side of the work and the other being on the opposite side of said work, and automatic mechanism for causing the tool to recede from the work before it reaches the said steady rest and for causing said tool to ap-

proach the work after it has passed said steady rest.

In testimony whereof I affix my signature in presence of two witnesses.

BENGT M. W. HANSON.
